UNITED STATES PATENT OFFICE.

EDWIN F. GUTH, OF ST. LOUIS, MISSOURI, ASSIGNOR TO ST. LOUIS BRASS MANUFACTURING COMPANY, OF ST. LOUIS, MISSOURI, A CORPORATION OF MISSOURI.

LIGHTING FIXTURE.

1,418,302.

Specification of Letters Patent. Patented June 6, 1922.

Application filed April 25, 1919. Serial No. 292,538.

To all whom it may concern:

Be it known that I, EDWIN F. GUTH, a citizen of the United States of America, residing at the city of St. Louis, State of Missouri, 5 United States of America, have invented a certain new and useful Lighting Fixture, of which the following is such a full, clear, and exact description as will enable any one skilled in the art to which it appertains to 10 make and use the same, reference being had to the accompanying drawings, forming part of this specification.

My invention relates to an improved lighting fixture and particularly to means whereby lamps of different sizes can be applied to the fixture and at the same time the proper relative position of the lamp filament with respect to a light shield or reflector may be maintained.

20 In the accompanying drawings, Figure 1 is a side view partly in cross section and partly in elevation of a fixture embodying my invention; Figure 2 is a vertical cross section of the fixture supporting member 25 and lamp socket and associated parts; and Figure 3 is a horizontal cross section on the line 3—3 of Figure 2.

1 represents a supporting shell to which the reflector 2 is connected by means of 30 thumb screws engaging with the collar on the reflector as shown. The light shield 3 surrounding the lamp 4 is supported from the reflector 2 by spindles 5.

The particular form of lamp receptacle 35 illustrated comprises a socket proper 6 and a threaded clamping member 7 which engages the outer surface of the threaded shell 8 attached to the lamp socket and adapted to receive the lamp. The plate 9 is provided with 40 a central opening receiving the reduced portion of the member 7 and is clamped between this member and the socket. This plate 9 is provided with three preferably integral arms 10 which extend downward and are provided

with bends forming shoulders which are 45 adapted to engage with the openings 11 in the shell 1. These openings 11 are in portions of the shell which are pressed out to form channels whereby the arms 10 are guided from one of the openings 11 to the other. As 50 additional means for preventing the plate 9 from turning relative to the socket 6, this socket is provided with a short lug 12 engaging with a correspondingly shaped recess in the plate 9. 55

Incandescent lamps of different candle power are of different size and over all length, consequently in order that the filament of a lamp of a larger size may occupy approximately the same position with respect 60 to the reflector and shield as the filament of a lamp of smaller size, the position of the lamp receptacle must be changed and it will be observed that this change is made possible in a very simple and convenient manner. The 65 arms 10 are resilient and only a comparatively slight pressure on the lamp is necessary to disengage them from one set of the openings 11 and move the receptacle to another set of openings higher or lower than 70 the first as desired. The channels in the shell 75 guide the engaging shoulders of the arms 10 from one opening to another.

Having fully described my invention, what I claim as new and desire to secure by Letters Patent of the United States is:

In a lighting fixture the combination with a shell provided with vertically aligned openings, of a two part lamp receptacle within said shell, means on said receptacle 80 having resilient extensions adapted to engage with the openings in the shell, said shell also being provided with a groove to guide the extensions of the plate from one opening in the shell to another. 85

In testimony whereof, I have hereunto set my hand and affixed my seal.

EDWIN F. GUTH. [L.S.]
